UNITED STATES PATENT OFFICE

91,803

DESIGN FOR A RADIO RECEIVER CABINET

Louis D. Canevari, Stockton, Calif.

Application January 25, 1934, Serial No. 50,508

Term of patent 7 years

To all whom it may concern:

Be it known that I, LOUIS D. CANEVARI, a citizen of the United States, residing at Stockton, in the county of San Joaquin and State of California, have invented a new, original, and ornamental Design for Radio Receiver Cabinets, of which the following is a specification, reference being had to the accompanying drawing, forming part thereof.

The figure is a view in perspective of a radio receiver cabinet, showing my new design.

I claim:

The ornamental design for a radio receiver cabinet, as shown.

LOUIS D. CANEVARI.
